Primary Examiner — Jennifer Rivard(74) *Attorney, Agent, or Firm* — Ryan A. Schneider; Troutman Sanders LLP(57) **CLAIM**

The ornamental design for a container for use in a washing process, as shown and described.

DESCRIPTION

FIG. 1 is a perspective view of a container of the present invention;

FIG. 2 is a front view of the container of FIG. 1;

FIG. 3 is a back view of the container of FIG. 1;

FIG. 4 is a side view of the container of FIG. 1;

FIG. 5 is the other side view of a container of FIG. 1;

FIG. 6 is a top view of the container of FIG. 1;

FIG. 7 is a bottom view of the container of FIG. 1;

FIG. 8 is a perspective view of another embodiment of a container of the present invention;

FIG. 9 is a front view of the container of FIG. 8;

FIG. 10 is a back view of the container of FIG. 8;

FIG. 11 is a side view of the container of FIG. 8;

FIG. 12 is the other side view of a container of FIG. 8;

FIG. 13 is a top view of the container of FIG. 8; and,

FIG. 14 is a bottom view of the container of FIG. 8.
